UNITED STATES PATENT OFFICE.

WALTER TEALE, OF HAMILTON, CANADA.

RAPID-FIRE PYROTECHNIC GUN.

SPECIFICATION forming part of Letters Patent No. 645,436, dated March 13, 1900.

Application filed August 28, 1899. Serial No. 728,721. (No model.)

To all whom it may concern:

Be it known that I, WALTER TEALE, a citizen of Canada, residing at Hamilton, in the county of Wentworth, in the Province of Ontario, Canada, have invented new and useful Improvements in Rapid-Fire Pyrotechnic Guns, of which the following is a specification.

My invention relates to rapid-fire pyrotechnic guns in which a circular-chambered cartridge-holder is revolved and operated by connected mechanism in conjunction with an automatic cartridge-feed.

The objects of my invention are, first, to discharge pyrotechnics from the gun with rapidity and in quick succession at public and private displays of fireworks; second, to discharge pyrotechnic signals for marine or military purposes; and, third, to afford facilities for the rapid and practical operation of the mechanism comprising the gun. I attain these objects by the mechanism illustrated in the accompanying drawings, in which—

Figure 1 is a side elevation of the pyrotechnic gun, one side of the casing being removed, also the stop-pin casing, and the lower semicircular flange of the cartridge-feed receptacle or hopper are removed, to show the mechanical movements, the cartridge-roller and the rear circular recoil-plate being in section. Fig. 2 is a rear end elevation showing mechanism to operate the pin in the aforesaid stop-pin casing, also the aforesaid semicircular flange of the cartridge-feed receptacle. Fig. 3 is a plan of the same. Fig. 4 is a rear elevation of the detached circular-chambered cartridge-holder, showing a series of cartridges formed as a belt capable of revolving with said holder and leaving the same when the cartridge is expended and when the same travels downward below the diametrical line of said cartridge-holder. Fig. 5 is an enlarged plan of the detached stop-pin with its casing; and Fig. 6 is an enlarged plan of a single cartridge, showing its attachment to ribbons to form a belt of a number of cartridges.

Similar letters and numerals refer to similar parts throughout the several views.

In the drawings the circular-chambered cartridge-holder is indicated by A and has a series of chambers or openings 2 on its periphery. Each said opening is capable of admitting freely and of holding a cartridge L. This

holder A is capable of revolving on its center through pin B. This pin passes through the front and rear vertical parts of the framework or casing C, which is extended rearward to contain certain inclosed operating parts which are inclosed by casing sides b. The rear circular recoil-plate 3 forms a part of the casing C and to which is attached the detachable cartridge receptacle or hopper D by means of its lower semicircular flange 4, which forms a shield for the left-hand side of the circular holder A. The lower reduced part of this hopper D is of sufficient size to allow only one cartridge to fall through and consecutively into one of the cartridge-openings 2, and so on in continuity as the holder A revolves. To feed and revolve this holder A, to stop the same, and to discharge the cartridges in quick succession is accomplished by means of the right-hand side operating-lever E. This operating-lever is pivoted to the center-pin 5, which passes through the frame, and from said pin 5 is loosely hung the arm F, which extends downward through a slot 6 in the casing as far as the lower extension of the said operating-lever E, when both the said lever E and the arm F are connected by the center-pin 7, to which is secured the stop-pin-operating arm H. When the said lever E is brought toward the rear, as shown, the cartridge-holder stop-pin J is withdrawn from the holder by the arm H engaging with the front part of the projecting pin 8 of said stop-pin. This pin 8 operates in the slot 9 of its casing K. A tension-spring M is supplied in this casing K to push the stop-pin J in the circular series of rear sockets N in the holder A to stop the same. Immediately the lever E is pushed forward toward the barrel I of the gun the stop-pin J commences to be freed and the pawl P, which is pivoted to the hub of the arm F, revolves the holder A by engaging the ratchet-teeth O in said holder A to bring a cartridge opposite to the striking-pin R and continuously. At this same time the side extension 10 of said arm F engages with the lever T, which is pivoted at 13 to the hammer S, to force the same to the rear or striking position, and immediately the said extension 10 has passed the arm T the hammer is then released to strike the pin R. This hammer operates in the slot G of the casing

and is pivoted at 17 to the casing and is capable of striking a forcible blow by means of the spring U being connected to the lower and rear part of the hammer by the pivotal connection V. By this quick movement of the operating-lever E to and fro the cartridges are brought to position in quick succession and discharged with great rapidity. W is a tension-spring to press slightly on the pawl P, and Y is a spiral tension-spring in rear of the arm T to push the same forward after the said pivotal arm T has been pressed rearward by the extension 10, when the same is brought downward by means of the operating-lever E. The said striking-pin R is provided with a spiral spring Z in order to free the cartridge-holder A from the pin and to bring the pin rearward to position with the hammer.

20 When operating the gun for pyrotechnic displays, a number of cartridges may be placed in the hopper D, the lower part of which is of a size to admit of only one following another in line, though the upper part is wider to admit several side by side. This hopper is capable of being removed by taking out the screws 14, as seen in Fig. 2 of the drawings, and the belt of cartridges may be used instead of the hopper. This belt of cartridges 30 is formed by a number being attached together at proper and uniform distances apart to conform to the distance apart of the cartridge-chambers, and are fastened by means of light ribbons 12 of suitable material and size, and must enter the cartridge-holder A from the side from which the hopper has been removed. It will be observed that the cartridge-chambers, the stop-pin sockets, and the ratchet-teeth of the revolving cartridge-holder 35 must be of corresponding equal number.

The barrel of the gun may be of suitable size and length and screwed or otherwise fastened to the forward projecting part 15 of the casing C as desired. It will be noticed that this part 15 has a transverse slot 16 to allow the cartridges to enter to central position and to pass through when expended.

Various changes in the form, proportion, and minor details of my invention may be resorted to without departing from the spirit and scope thereof. Wherefore

What I claim as my invention, and desire to secure by Letters Patent, is—

1. A pyrotechnic gun of the character described, comprising a circular cartridge-holder having a series of open cartridge-chambers around its periphery, a circular series of corresponding sockets in the rear side thereof, and a corresponding number of ratchet-teeth circularly arranged on said same side, a casing having a pin for said holder to revolve on, a hopper attached to said casing and capable of allowing cartridges to fall consecutively into said open chambers, a side operating-lever pivoted to a pin

through said casing, an arm hung from said pin and connected to the extended end of the operating-lever to operate mechanism connected therewith to revolve and to stop the cartridge-holder and to continuously discharge said cartridges, substantially as herein set forth.

2. A pyrotechnic gun of the character described, comprising a circular cartridge-holder having open cartridge-chambers 75 around its periphery, a corresponding number of sockets in the rear side of the holder to receive a stop-pin, a corresponding number of ratchet-teeth on the said rear side to receive the end of a pawl to revolve said holder on a center-pin through the casing thereof, a side operating-lever, pivoted to a through-pin of the casing, a connecting-arm provided with said pawl pivoted thereto and hung from said pin and connected to the lower end of said operating-lever, and mechanism therewith to revolve and to continuously feed and discharge the cartridge-holder, substantially as set forth.

3. In a pyrotechnic gun the combination 90 of the circular cartridge-holder having open cartridge-chambers on its periphery, a corresponding number of sockets to receive a stop-pin in the rear side of the holder, a corresponding number of ratchet-teeth on said 95 rear side to receive a pawl to revolve said holder on a center-pin in the casing thereof, said pawl connected to a side operating-lever by a lower arm hung from the pivotal center of said operating-lever, the lower end of said arm connected to the lower extended end of the operating-lever by a through-pin having an arm to operate said stop-pin, a hammer pivoted to said casing and to engage the strike-pin and connected to said operating-lever by mechanism, substantially as set forth.

4. The combination of the circular cartridge-holder having a number of open cartridge-chambers on its periphery, a corresponding number of stop-pin sockets, in the rear side thereof, a corresponding number of ratchet-teeth on said rear side of said cartridge-holder to revolve the same on a center-pin of the casing by a pawl engaging said teeth, actuated by a side operating-lever connected to said pawl, a stop-pin, an arm connected to the lower through-pin of said operating-lever to operate said stop-pin, a hammer pivoted to said casing to engage the strike-pin, and connected to said operating-lever by mechanism to revolve and to stop the cartridge-holder, and to continuously feed and discharge the same, as set forth.

In testimony whereof I affix my signature in presence of two witnesses,

WALTER TEALE.
